DROP TUBE AND SUPPORT FIXTURE

Alvin H. Baer, Carbondale, Pa., assignor, by mesne assignments, to Worthington Pump and Machinery Corporation, Harrison, N. J., a corporation of Virginia

Application June 29, 1934, Serial No. 733,042

12 Claims. (Cl. 62—159)

My present invention relates to means for mounting the air delivering drop tubes which are customarily disposed in the cans in which cakes or blocks of ice are frozen, and more particularly to improved means for permitting swinging movement of the drop tube in respect to the horizontal air pipe extending above and across a row of cans without leakage of air.

A further object of the invention is to provide a drop tube hanger fitting capable of slight movement along its supporting pipe so that the drop tubes may be properly centered with respect to the cans despite occasional endwise displacement of the pipe from which they are hung, or incorrect boring of the holes therein or slightly different placing of the cans.

Another object is to provide a flexible tube connection between the supply air pipe and an air passage in the drop tube hanger, yet so to counterbalance the weight of the hose that the drop tube always hangs vertically, this despite the fact that the drop tube hanger fixture but loosely encircles the supply air pipe and has but a small support surface in rockable contact therewith.

Another object is to provide improved means for effecting subdivision of the air stream emanating from the lower end of the drop tube.

The main object is to so support the tube that it may freely swing in any direction in the can and with such slight resistance that varying air and water current in the can may cause the lower end of the tube to move in the direction of the maximum or minimum horizontal dimension of the can.

Other objects are to provide a fitting of the character noted which is simple and practical in construction, rugged and durable in use, all of the parts of which are readily removable for purposes of convenient repair and assembly, and a fitting which is well suited to meet the requirements of economical manufacture.

The invention may be more fully understood from the following description in connection with the accompanying drawing wherein:

Fig. 1 is a fragmentary diagrammatic plan view of one corner of an ice freezing apparatus showing a number of cans and part of a header feeding a lateral air pipe upon which my improved drop tube fillings are hung.

Fig. 2 is an enlarged broken view partly in vertical section and partly in side elevation showing the manner in which a drop tube is suspended in a can.

Fig. 3 is a view of the tube and fitting partly in

side elevation and partly in vertical section and taken at right angles to Fig. 2,

Fig. 4 is a top plan view of the fitting, and

Fig. 5 is a section through another form of fixture and in a plane at right angles to the air pipe.

In Fig. 1, 10 represents a brine filled tank and 11, a plurality of rows of standard ice cans supported in the brine in conventional fashion. The system for delivering air to the water in the cans 10 during preliminary or partial freezing thereof includes a compressed air header 12 supplied from any suitable source (not shown). A plurality of laterals such as 13 are connected to the header 12 and each extend above a row of cans 15 11. My present invention is concerned with the drop tubes, the means for supporting them from the laterals and for delivering air to them.

The details of one of my improved drop tube fixtures are shown in Figs. 2 to 4 inclusive.

The fixture includes an eye portion 14 to encircle the pipe 13 and a pendent stem portion 15 integral with the eye. Eye 14 is of relatively thin flat metal of substantially greater minimum diameter than the outside diameter of pipe 13 25 and is slightly elongated from top to bottom.

Arranged at the top of the eye and internally thereof is an arcuate rounded rib 16 serving as a saddle which rests upon the top of the pipe 13 so that the eye is rockably mounted on the pipe. 30 The eye is provided about midway of its sides with a pair of diametrically opposite openings 17 and through one of these openings an L-shaped hose fitting 18 is screwed into a suitable opening in the pipe 13. The diameter of the outside arm of the fitting 18 which screws into the pipe 13 is considerably less than the minimum diameter of opening 17 so that slight adjustments of the eye member along or about the air pipe may be had without disturbing the fitting 18.

The outer arm of this L-shaped fitting is disposed in horizontal position and parallel to pipe 13. Air flowing from the pipe 13 through the hollow fitting 18 is carried by a length of flexible hose 19 to a nipple 20 projecting laterally from 45 stem 15. Member 18 and nipple 20 both have the customary peripheral grooves therein for frictional engagement with the ends of the rubber hose 19 which are forced over them.

The horizontal air passageway 22 in the nipple 20 communicates with a vertical passageway 23 having an outlet at the bottom of the stem 15, the lower portion of this stem being bevelled to afford a tapered annular shoulder 24. Above 50 55

the shoulder the stem is externally threaded as at 25.

The drop tube 26 has its upper end flared as at 27 to seat on the tapered shoulder 24 and this flared tube mouth is pressed against the shoulder and an effective air seal afforded by a nut 28 which screws onto the threads 25 and which is internally tapered as at 29 to engage the flared drop tube mouth and force it against the shoulder. 10 The tube near its upper end is encircled by a rubber retaining ring 30 which prevents the nut 28 from falling off when unscrewed.

In order to direct the discharging air stream from the lower end of the tube in opposite directions to assure a maximum amount of agitation of the water in the can, the lower end of the tube is provided with a pair of diametrically opposed slots 31. These slots permit the air to escape from the two opposite sides of the tube facing in the direction of the greatest horizontal dimension of the can so that the streams of air are directed up along the opposite sides of the tube and induce a down-flow of water at the opposite side of the can. The slots are far more inexpensive to form than any partition in the tube.

The weight of the hose 19 and the weight of the nipple 20 normally tends to rock the eye 14 on its seal 16 and throw the tube 26 out of the desired vertical position. Air pressure in the hose tends to stiffen it and resist swinging of the drop tube in one direction. To overcome these tendencies I employ a counter-balancing member integral with the stem portion of the fixture. This counter-balance illustratively comprises a laterally projecting cylindrical extension 32 disposed diametrically opposite the nipple 20. In addition to serving as a counter-balance it may be used as a handle for shifting the entire fixture laterally along the pipe 13. It will be apparent from the foregoing that the drop tube may freely swing on the pipe in the plane of the latter by rocking on the rib 16 as a knife edge and may also freely swing on the pipe by the endwise sliding of the rib. Thus the pipe is not restrained against movement in any direction. Damaged nozzle members 18 or drop tubes 26 etc. may be readily replaced with new ones. Furthermore it is unnecessary to remove the entire air lateral where the repair of one drop tube or fixture is required.

Although in the construction above referred to the eye 14 encircles the air pipe, this is not essential as it is only important that the fixture be freely supported on the air pipe and that the drop tube be suspended from below the air pipe. Thus one side of the eye may, if desired, be omitted. In Fig. 5 the fixture includes a curved arm 14a similar to the eye 14, but with one side omitted. This has the flange 16 engaging the under side of the pipe and the pendant stem portion beneath the air pipe. The air fitting 18a extends through an aperture in the arm 14a and permits the fixture to rock or swing in any direction, but normally holds it against being accidentally discharged from the air pipe.

Having thus described my invention, what I claim as new and desire to secure by Letters Patent is:—

1. A drop tube support fixture including an eye to encircle an air delivery pipe and to support a drop tube, said fixture having a supporting projection for engaging the upper side of the pipe and permitting the tube to swing in any direction, a stem portion having a vertically disposed air passageway therein for communica-

tion with said drop tube and a hose receiving nipple having a passageway therein communicating with the passageway in the stem.

2. An air delivery and tube support assemblage of the character described, including in combination with a horizontal air pipe, a fixture loosely suspended from the pipe and a drop tube carried by the fixture, an air outlet fitting at the pipe, a hose receiving nipple at the fixture, a flexible hose connecting the fitting and nipple, means for conveying air from the hose through the fitting to the drop tube and a boss integral with the fitting for counter-balancing the weight of the hose to maintain the drop tube in vertical position.

3. An air delivery and tube support assemblage of the character described, including in combination with a horizontal air pipe, a fixture loosely suspended from the pipe and a drop tube carried by the fixture, an air outlet fitting at the pipe, an air inlet nipple at the fixture, a flexible hose connecting the fitting and nipple and means for conveying air from the hose through the fixture to the drop tube and means for counter-balancing the weight of the hose to maintain the drop tube in vertical position.

4. A drop tube support fixture including an eye to encircle an air delivery pipe, a stem portion having a vertically disposed air passageway therein, said stem at its lower end being bevelled to afford an abutment for the flared upper end to a drop tube and being externally threaded above said abutment for engagement with a nut which retains the flared drop tube mouth against the abutment.

5. A drop tube support fixture including an eye to encircle an air delivery pipe, a stem portion having a vertically disposed air passageway therein, said stem at its lower end being bevelled to afford an abutment for the flared upper end to a drop tube and being externally threaded above said abutment for engagement with a nut which retains the flared drop tube mouth against the abutment, and a hose connection for conveying air from the pipe to the hollow stem.

6. An air delivery and tube support assemblage of the character described, including in combination with a horizontal air pipe, a fixture loosely suspended from the pipe and a drop tube carried by the fixture, an air outlet fitting at the pipe, an air inlet nipple at the fixture, a flexible hose connecting the fitting and nipple means for conveying air from the hose through the fixture to the drop tube, a counter-balancing extension arranged at the side of the stem opposite the nipple.

7. A fitting of the class described including a portion to engage and be suspended from a horizontal air pipe, a pendent drop tube carrying extension integral with the support portion means for conveying air from the pipe to the drop tube carrying extension, a hose connection for conveying air from the pipe to the drop tube carrying portion and means to counter-balance the weight of the hose.

8. A drop tube fixture including an eye adapted to encircle a supporting pipe, a tube carrying extension fixed with respect to the eye, said extension having an air passageway therein communicating with the tube and a flexible hose connection for conveying air from the supporting pipe to the passageway in the fixture.

9. Apparatus for freezing water ice, including a plurality of ice freezing cans, an air pipe ar-

ranged thereabove, drop tubes extending into the cans for delivering compressed air beneath the surface of the water to be frozen, supporting fixtures, and rounded arcuate ribs on said supporting fixtures engaging said pipe whereby said supporting fixtures are loosely suspended on the air pipe and may swing in any direction in the cans.

10. Apparatus for freezing water ice, of the character which includes an air pipe arranged above a plurality of ice freezing cans and drop tubes extending into the cans for delivering compressed air beneath the surface of the water to be frozen, said apparatus being characterized by the fact that the drop tubes are loosely suspended by supporting fixtures from the air pipe, and the fixtures each have a rib extending across the supporting pipe and slidable endwise on the

pipe and tiltable on the pipe to permit swinging of the pipe in any direction.

11. In combination with an air delivery pipe, a drop tube supporting fixture including an eye to encircle said pipe, an arcuate rib rounded in cross section formed upon the interior of said eye and engaging the pipe to support the eye from the pipe and permit limited swinging movement of the eye in any direction, a drop tube carried by said eye, and a flexible connection between the pipe and drop tube.

12. In combination, an air delivery pipe, a drop tube fixture including an air delivery pipe engaging member loosely suspended from the pipe and having its lower end beveled, a drop tube having its upper end flared to fit said beveled end, and means for clamping said flared end against the beveled end of said member.
